UNITED STATES PATENT OFFICE

147,141

DESIGN FOR A COMBINATION KITCHEN UNIT

Joseph Oros, Inkster, Mich.

Application September 24, 1945, Serial No. 122,270

Term of patent 3½ years

(Cl. D33—13)

To all whom it may concern:

Be it known that I, Joseph Oros, a citizen of the United States, residing at Inkster, county of Wayne, State of Michigan, have invented a new, original, and ornamental Design for a Combination Kitchen Unit, of which the following is a specification, reference being had therein to the accompanying drawings, forming a part thereof, in which

Fig. 1 is a perspective view illustrating a combination kitchen unit embodying a design in accordance with the present invention.

Fig. 2 is an end elevation viewed from the right-hand end of Fig. 1.

Fig. 3 is an end elevation viewed from the left-hand end of Fig. 1.

I claim:

The ornamental design for a combination kitchen unit, substantially as shown.

JOSEPH OROS.
